UNITED STATES PATENT OFFICE.

ARTHUR STOLL, OF ARLESHEIM, NEAR BASEL, AND WALTER KUSSMAUL, OF BASEL, SWITZERLAND, ASSIGNEES TO THE FIRM CHEMICAL WORKS FORMERLY SANDOZ, OF BASEL, SWITZERLAND.

PROCESS FOR THE OXIDATION OF ALDOSES.

No Drawing. Application filed May 16, 1927, Serial No. 191,922, and in Germany June 12, 1925.

The oxidation of aldoses, e. g. glucose, to the respective monocarboxylic acids with hypobromite or hypoiodite is known and can be performed so exactly that it was possible to work out a dosage of sugars making use of this principle (see Willstätter and Schudel, Berichte der deutschen chemischen Gesellschaft 51, 780, 1918). Further, Höning and Tempus (loc. cit. 57,789, 1924) prepared gluconic acid by oxidizing glucose with barium hypobromite. The reaction can not be so easily performed if hypochlorites are used. Glucose f. i. is in part further degraded, even so far as to form oxalic acid and carbonic acid. (Bräutigam, Pharm. Ztg. 46, 636 and Chem. Zentralblatt 1901, II, 680), whilst the gluconic acid has up to now not yet been isolated from the products of reaction. According to our own trials, the oxidation with hypochlorites proceeds through gluconic acid. It has even been possible under certain working conditions to identify this intermediate oxidation product. The above described method is unsatisfactory from the technical point of view as on the one hand a certain rather important quantity of glucose is not oxidized and on the other hand a considerable amount of further degraded acids is formed, so that the yield of pure gluconic acid is quite insufficient.

Further, another method has been described (Journ. Soc. Chem. Ind. 41, p. 28-29, 1922) which consists in the addition of $\frac{1}{4}$ equivalent of calcium bromide when oxidizing the sugars with chlorine. The hypochloric acid which is set free in this process is from time to time neutralized with calcium carbonate. A few hours are necessary at the very least for this process and it can only be performed in an apparatus resistant to hydrochloric acid. Moreover at the high temperature used, considerable quantities of bromine set free from the calcium bromide by chlorine escape, and this can certainly be considered as a serious disadvantage for industrial purposes. The new process is much cheaper than that of the literature as cited, because it necessitates at most one quarter of the quantity of bromine otherwise used.

A process has now been found according to

which it is possible to successfully employ the cheaper hypochlorite for the oxidation of aldoses to the respective monocarboxylic acids, if only very small quantities of bromine or iodine, even in the form of their salts, are added to the oxidation mixture. The presence of bromine or iodine influences this reaction otherwise so destructive, in such a manner that the oxidation stops at the monocarboxylic acid, viz. all of the aldose can be transformed into the monocarboxylic acid before the oxidation process advances. Under these conditions the yields are as good as if hypobromite or hypoiodite would have been used as oxidizing agent and this is the case with all aldoses coming into consideration, such as for example glucose, galactose, mannose, lactose and maltose. The new process possesses also the advantage that it is carried out in an alkaline medium, which does not affect the material of the apparatus and from which no bromine escapes, whilst in the known process, on account of an acid medium, corrosion of the apparatus and escape of bromine take place.

The quantity of bromine or iodine to be added, e. g. in the form of their soluble salts, may be less than $\frac{1}{10}$ of an equivalent of the amount of hypochlorite necessary for the oxidation. Alkali, alkali earth or magnesia may be used with the same effect as bases. Further, the process may be performed in a variety of ways. For instance, it is quite indifferent whether a definite hypochlorite solution is added to a solution of sugar containing bromine or iodine or whether chlorine gas is introduced into a mixture of alkali with a salt of hydrobromic or hydroiodic acid and the sugar. It is important for a good reaction, that the process be performed at a low temperature. The isolation of the monocarboxylic acids is carried out in a known manner.

The following examples illustrate the new process.

Example 1.

An oxidizing solution is prepared by introducing at a low temperature 24.3 g. of chlorine in 590 ccm. of a 10% caustic potash lye. This solution is then added in small

portions to a well-cooled solution of 60 g. of glucose and 8 g. of sodium bromide in 250 ccm. of water. It is advantageous to add the last portions more slowly. The reaction 5 is finished when iodide starch paper remains unaltered. The mass is then concentrated to a sirupy consistency, without regard to the precipitation of potassium chloride that takes place. The gluconic acid is then 10 liberated by acidulating with hydrochloric acid until Congo paper turns to a steel blue, the crystals of potassium chloride are filtered off and the acid is neutralized with milk of lime. After some hours the mass becomes 15 solid and the gluconate of calcium is filtered off. Raw product 62 g. The product can be purified by recrystallization from hot water; on incineration it leaves 13.51% of CaO (0.2183 g. gave 0.0295 g. CaO), calculated for $(C_6H_{11}O_7)_2Ca = 13.03\% CaO$.

Example 2.

A solution of 60 g. of glucose in 250 ccm. of water is mixed with milk of lime obtained from 30.8 g. of lime; then 3.5 g. of sodium bromide are added. Into this mixture 24.5 g. of chlorine gas are introduced while cooling and agitating. As soon as the oxidation begins, the temperature rises. 30 By cooling and regulating of the chlorine supply, the temperature should be kept below 15° C. When iodide starch paper indicates that the whole of the oxidizing agent has been spent, the lime is precipitated by 35 adding 78 g. of sodium sulphate. The raw solution of sodium gluconate is then concentrated, the gluconic acid liberated from its sodium salt and concentrated to a sirupy consistency. The greater amount of the 40 common salt precipitates and is eliminated by filtering off or hydro-extracting. The concentrated solution of gluconic acid is worked up as indicated in Example 1.

Example 3.

45 11.5 g. of magnesia usta are hydrated with 200 ccm. of water by heating them for three hours on the waterbath. Then 2.6 g. of bromine are added to 20 ccm. of this paste 50 whilst cooling. The reaction product thus obtained is then added to a well-cooled solution of 30 g. of glucose in 120 ccm. of water. The rest of the magnesium hydroxide paste is treated with 10.7 g. of chloride 55 gas and the solution thus obtained is added slowly and under cooling to the sugar solution. After the oxidizing agent is spent, the solution is concentrated in vacuo and the resulting syrup (ca. 60 ccm.) is mixed under 60 stirring with 1 liter of alcohol (95%). The magnesium salt separates and solidifies over night forming a crystalline deposit. It is filtered off, washed with alcohol and ether, to furnish 22.7 g. The product may be re-

crystallized from hot diluted alcohol. It is dissolved in hot water and hot alcohol is added thereto until the precipitation begins; on cooling the salt separates out in form of indistinct white crystals. The pure salt loses only slowly its crystal-water at 98° C., even in a high vacuo (nearly $3H_2O$). On incineration 10.11% of MgO are obtained (0.1988 g. gave 0.0201 g. of MgO). Calculated for $(C_6H_{11}O_7)_2Mg = 9.73\% of MgO$.

Example 4.

30 g. of galactose are dissolved in 100 ccm. of water, then a solution of 2.6 g. of bromine in 15 ccm. of milk of lime (from 1.5 g. of CaO) is added to the well cooled mixture. 50 The oxidation is then carefully performed as in the preceding examples with a solution of hypochlorite obtained from 135 ccm. of milk of lime (from 13.5 g. of CaO) and 11 g. of chlorine. After the oxidation is finished, the solution is concentrated to 80 ccm. On cooling, a part of the galactonate of calcium separates out and can be filtered off. A further quantity is obtained by adding alcohol to the filtrate. Yield: 29.1 g. of the recrystallized salt. The salt loses 14.9% of its weight in a high vacuo at 100° C. (2 molecules). On incineration 13.39% of CaO are obtained (0.2412 g. gave 0.0323 g. of CaO). Calculated for $(C_6H_{11}O_7)_2Ca = 13.03\% of CaO$.

Example 5.

To a solution of 180 g. of lactose in 1 liter of water, a solution of 6.3 g. of iodine in 23 ccm. of a milk of lime containing 2.3 g. of CaO is added. The oxidation started by this small quantity of hypoiodite, is then continued by a hypochlorite solution formed by introducing 33.8 g. of chlorine into 440 ccm. of milk of lime containing 44 g. of CaO. The only feebly muddy solution is then concentrated and the product of oxidation precipitated with alcohol. Dissolved in hot water, the salt separates on addition of alcohol in form of fine, clear crystals combined to crusts. Yield: 146 g. The salt has been proved to be a double salt of lactobionate calcium and chloride of calcium. The crystals lose their water of crystallization very slowly even in a high vacuo at 100°-105° C. After 20 hours of drying the loss is of 11.98%. The salt thus dried contained 9.33% of Ca (0.2111 g. gave 0.0669 g. of $CaSO_4$) and 8.28% of Cl (0.2318 g. gave 0.0776 g. of AgCl). Calculated for $(C_{12}H_{21}O_{12})_2Ca \cdot CaCl_2 = 9.26\% of Ca$ and 8.19% of Cl.

The oxidation of maltose with hypochlorite can be performed in an analogous manner.

What we claim is:

1. A process for the oxidation of aldoses

to the respective monocarboxylic acids, consisting in treating aldoses in an alkaline solution with hypochlorites in the presence of a salt of a halogen of higher molecular weight than chlorine.

2. A process for the oxidation of aldoses to the respective monocarboxylic acids, con-

sisting in treating aldoses in an alkaline solution with hypochlorites in the presence of a salt of bromine.

In witness whereof we have hereunto signed our names this 4th day of May 1927.

ARTHUR STOLL.
WALTER KUSSMAUL.
